Attorney, Agent, or Firm—Zarley, McKee, Thomte,
Voorhees, & Sease[57] **CLAIM**The ornamental design for a hamper, as shown and
described.**DESCRIPTION**FIG. 1 is a front perspective view of a hamper, showing my
new design;

FIG. 2 is a top plan view thereof;

FIG. 3 is a bottom plan view thereof;

FIG. 4 is a plan view of the floor thereof, shown separately
for ease of illustration, the opposite side being a mirror
image;FIG. 5 is a cross sectional view taken along line 5—5 of FIG.
1, shown without the outer frame for ease of illustration;FIG. 6 is a cross sectional view taken along line 5—5 in FIG.
1 of an alternate bottom embodiment with the remaining
views being the same as disclosed in FIGS. 1, 7—9;

FIG. 7 is a front elevational view thereof;

FIG. 8 is a rear elevational view thereof; and,

FIG. 9 is an elevational view thereof with the opposite end
being a mirror image thereof.The broken line showing of a hamper lid in FIGS. 1, 7, 8 and
9 is for illustrative purposes only and forms no part of the
claimed design. The cross-line pattern which is partially
shown for ease of illustration, represents a conventional
fabric and is understood to repeat uniformly throughout the
indicated area.**1 Claim, 9 Drawing Sheets***Fig. 1*
